UNITED STATES PATENT OFFICE.

EDMUND A. WITTENBORN, OF NEW BRAUNFELS, TEXAS.

VEGETABLE-CUTTER.

1,287,552.

Specification of Letters Patent. Patented Dec. 10, 1918.

Application filed April 12, 1918. Serial No. 228,170.

To all whom it may concern:

Be it known that I, EDMUND A. WITTENBORN, a citizen of the United States, residing at New Braunfels, in the county of Comal and State of Texas, have invented new and useful Improvements in Vegetable-Cutters, of which the following is a specification.

This invention relates to vegetable cutters and aims to provide a device of this character which may also be used as a grater.

To this end the invention includes a receptacle mounted for rotation and carrying upon its upper surface or lid, cutters or graters, which act upon the vegetables being cut or grated, the latter being deposited within the receptacle through openings in said lid.

The invention also includes a novel form of vegetable holder, which is disposed above the lid and holds vegetables in such position that a shearing cut is obtained.

The invention further includes means for removably securing the receptacle to the operating mechanism, so that the former may be removed for cleaning or for other purposes.

With the above and other objects in view the invention still further includes the following novel combinations and arrangement of the various mechanisms, which will be hereinafter more specifically described and illustrated in the accompanying drawings, in which:

Figure 1 is a side elevation of the vegetable cutter embodying the present invention;—

Fig. 2 is a top plan view of the same;

Fig. 3 is a bottom plan view of the receptacle removed from the remainder of the mechanism and illustrating the manner of securing one of the operating gears thereto;

Fig. 4 is a fragmentary sectional view on the line 4—4 of Fig. 2;

Fig. 5 is a plan view of the grater lid for the receptacle; and

Fig. 6 is a view similar to Fig. 3 showing the modified means of securing the gear to the receptacle.

Referring in detail to the drawings, like characters of reference denote corresponding parts throughout the several views.

In the form of the invention illustrated, there is provided a frame, which may be either cast or formed of malleable material and bent to provide upper and lower bearing arms 10 and 11 respectively, the latter being

extended and folded upon itself to provide an additional bearing arm 12, which is aligned with a standard 13. The bearing arms 10 and 11 support a shaft 14, which has secured at one end a beveled gear 15 and has its opposite end extended through the bearing arm 11 where it may be secured in position by means of a cotter pin 16 or other suitable fastening device. Mounted within bearings 60 in the arm 10 and the standard 13 is a crank shaft 17, which has secured upon one end a beveled gear 18, which meshes with and drives the gear 15 when operated by a handle 19, located at the opposite end of the 65 shaft 17. The above geared frame is designed to be secured to a table T or other support through the medium of a clamp formed by the member 20 carried by the frame, and the clamping screw 21.

The gear 15 has formed thereon or secured thereto radial arms 22, which terminate in angular extensions 23, the latter being tapped to receive set screws 24. Adapted to be removably secured to the arms 22 is a preferably cylindrical receptacle 25, which is provided with a lid 26, adapted to be removably secured thereto through the medium of a bayonet slot and pin connection 27. The lid 26 is provided with radially disposed slots 28, in which are positioned cutting blades 29, so that when the vegetable is held in position upon the lid of the receptacle, the knives slice the said vegetable, the slices being deposited within the receptacle through the 70 slots 28.

For holding the vegetable in position above the lid 26, there is provided an arm 30, which may be formed upon or secured to the standard 13. The free end of the arm is 80 provided with a hook 31, the vegetable being positioned within the angle formed by the arm and hook for action upon it by the cutters.

The lid shown in Fig. 5 is similar to the 100 one previously described, in that it is provided with a bayonet slot connection, but instead of the slots and blades 29 and 29 respectively, a grating surface 32 is formed in the lid, the material grated from the vegetable passing through into the receptacle.

In Fig. 6 the arms 22 are illustrated as connected to the bottom of the receptacle by means of the screws 33.

Various other changes may be made in the 110 form, proportion and minor details of construction and the right is reserved to make

any changes that will properly fall within the scope of the appended claim.

Having described the invention, what is claimed is:—

- 5 A vegetable cutter embodying a frame, a receptacle, actuating mechanism therefor carried by the frame, means for attaching

said mechanism to said receptacle, cutters disposed above and carried by the receptacle and a vegetable holder located above the cutters. 10

In testimony whereof I affix my signature.

EDMUND A. WITTENBORN.
